United States Patent Office

Des. 182,794

Patented May 20, 1958

182,794

LOUD-SPEAKER ENCLOSURE

Charles Eames, Pacific Palisades, Calif., assignor to
Stephens Tru-Sonic Inc., Culver City, Calif., a corpora-
tion of California

Application February 13, 1957, Serial No. 44,862

Term of patent 14 years

(Cl. D26—14)

Fig. 1 is a perspective view of a loud-speaker enclosure showing my new design;

Fig. 2 is a front elevational view;

Fig. 3 is side elevational view;

Fig. 4 is top plan view;

Fig. 5 is a cross-sectional view thereof, taken on line 5—5 in Fig. 2.

I claim:

The ornamental design for a loud-speaker enclosure, as shown.
